UNITED STATES PATENT OFFICE.

WALTER A. TRINLER, OF RUTHERFORD, NEW JERSEY.

MACHINE FOR HANDLING PAVING MATERIAL.

1,217,533.

Specification of Letters Patent. Patented Feb. 27, 1917.

Application filed April 19, 1916. Serial No. 92,162.

To all whom it may concern:

Be it known that I, WALTER A. TRINLER, a citizen of the United States, residing at Rutherford, in the county of Bergen and 5 State of New Jersey, have invented certain new and useful Improvements in Machines for Handling Paving Material, of which the following is a specification.

The present invention relates to a machine 10 arranged and constructed for the purpose of handling the blocks or bricks used in the construction of pavements.

The objects of the invention are, to provide an endless carrier adapted to receive 15 and transport paving bricks or blocks, which endless carrier will move in a horizontal plane and will remain, throughout its length, a uniform height from the ground level, which height will be proper to allow 20 the workmen to remove the bricks from the conveyer while in the stooping position assumed in pavement laying; to provide suitable means for driving the conveyer, and to allow a reversal of the direction of travel 25 of the conveyer when desired; to provide a trackway upon which the conveyer travels; to provide tractor means for the framework; to provide motor power for operating said tractor means; to provide means per- 30 mitting of a reversing of the direction of movement of the tractor means; and also to provide means permitting the tractor means on one side to be driven independently of the tractor means on the other side and thus 35 effect a steering of the machine.

The invention further consists in the features of construction and combination of parts hereinafter described and claimed.

In the drawings:

40 Figure 1 is a front view of an assembled machine embodying the features of the present invention;

Fig. 2, a plan view of the machine of Fig. 1;

45 Fig. 3, a cross section of the machine on a somewhat enlarged scale;

Fig. 4, a sectional detail of the conveyer and one of the driving members therefor; and

50 Fig. 5, a detail of the conveyer member, showing the trackway and rollers attached to the conveyer traveling upon the trackway.

In the art to which the present invention 55 relates, in the laying of pavements it is customary to pile the paving bricks or blocks

upon one or both sides of the street, and to carry the bricks to the workmen performing the laying operation. If this process is carried on by hand, it is necessarily 60 slow and results either in a waste of time or the employment of a considerable number of workmen to transport the bricks or blocks. In the present invention it is intended to convey these bricks or blocks to 65 the workmen by mechanical means and to construct the machine so that it is cheap and simple, can be easily handled and manipulated, and can be built sufficiently cheap to warrant its adoption by the contractor. 70

Referring now to the drawings, the machine comprises a framework 6, which, as shown, consists of an upper section 7 and a lower section 8. Each of these sections is of angle-formation, as will be seen more 75 clearly from Fig. 3. The upper section has the angled portion 9 turned inward to form a frame along the inner edge of said section. The lower section has the angled portion 10 turned outward to form a track- 80 way for the conveyer, which will be more fully hereinafter described. The two sections are connected together in any suitable manner, as, for instance, plates 11.

Still referring to Fig. 3, it will be seen 85 that the lower portion of this framework is open so that in fact the framework is of hollow construction and open at its lower end. The function of this will more fully hereinafter appear. Suitable cross supports 90 12 are provided, and to these cross supports are mounted wheels 13, which are of a nature to drive a caterpillar chain 14. There are two of these caterpillar tractor wheels provided, one on each side, as will be seen 95 from Fig. 1. I prefer the use of this caterpillar construction because of the fact that it gives a broad base for the tractor members, so that they do not depress or cut into the previously laid pavement. 100

By making the framework so that it is open at its lower end, I can extend the tractor members up inside of the frame. This allows the frame to be placed close to the ground, and will bring the conveyer at a suitable distance—probably about a foot from the ground line—which is necessary to allow the workmen to readily and quickly remove the blocks from the conveyer without moving from the stooped position assumed in pavement laying. 110

Upon the upper surface of the frame I

provide, in the construction shown, covering plates 15. The frame 6 as a whole is made in two parts, one of which is designated by the numeral 16, and the other by the numeral 17; and these parts are joined together, as shown, by a bolted filler block 18. By loosening the bolts of this filler block, the parts of the frame can be moved with respect to one another so as to lengthen the frame or shorten it, in correspondence to the width of the street being paved.

I employ, in the construction shown, a gas motor 19 for driving the tractor members. The drive shaft of the motor is provided with a pinion 20 meshing with a gear 21, which drives a cross shaft 22. This cross shaft carries a pinion 23 moved in and out of driving engagement by means of a suitable clutch 24. The pinion 23 meshes with a gear 25 on a driven shaft 26; and on this driven shaft is a sprocket 27 for driving a chain 28 leading to the tractor on one side. Also on the shaft 26 is a sprocket 29 driving a similar chain 28 to actuate the tractor on the opposite side.

The sprocket 27 is thrown in and out of driving relation by means of a clutch 30, and the sprocket 29 is thrown in and out of driving relation by a clutch 31. By actuating the clutch 24, the entire driving connection to both tractors is interrupted and the machine remains stationary, although the engine is running. When both clutches 30 and 31 are thrown into engagement, both tractors are driven and the entire machine moved straight forward or back. However, if the clutch 30, for instance, is thrown into engagement and the clutch 31 out of engagement, then only the tractor driven by the sprocket 27 will be actuated, which will effect a turning of the machine in one direction. If the clutch 31 is thrown in and the clutch 30 out, the machine will then be driven in the opposite direction through the actuation of only the tractor member associated with the sprocket 29. Of course, the particular means of driving the tractors is subject to variation and modification.

50 Mounted idly upon the shaft 22 is a gear 32 controlled by a clutch 33. This gear 32 meshes with a gear 34, which is secured to a shaft 34^a having on its other end a gear 35, which meshes with the gear 25, and by this means a reverse motion is imparted to the shaft 26 to effect a reverse drive of the tractors.

The conveyer comprises a link belt or chain 36 of suitable construction, joined to which are a plurality of plates 37 in overlapped relation. These plates are mounted so that they pivot about the pins 38, which connect them to the chains. This permits the conveyer to turn around the corners of the frame. A U-shaped member 39 is se-

cured to the plates and to the chain, which U-shaped member serves as a mounting for a roller 40 that travels on the flange 10 of the lower section of the frame. This flange, therefore, constitutes a trackway for the conveyer, which prevents the conveyer from sagging during operation.

By making the conveyer of sectional formation, the length of it can be increased or decreased in accordance with the shortening or lengthening of the frame of the machine. The conveyer is driven by a series of sprockets 41, which are mounted in bearings 42 within the frame. As shown, there is one of these sprockets at each corner of the frame, and the sprocket closest to the motor 19 (see Fig. 2) is driven by means of a bevel gear 43 and bevel pinions 44 on a sleeve 44^a which is mounted on the shaft 22. By means of a lever 45, the position of the pinions 44 can be shifted to bring one or the other into engagement with the gear 43. This enables a reversal to be made in the direction of travel of the conveyer. An adjusting mechanism 46 is shown for one of the sprockets to allow it to be moved in and out to take care of the slack which may develop in the conveyer.

From the foregoing, it will be apparent that the machine is cheap and simple of construction for the work intended, and contains no involved nor complicated parts that would be liable to become disarranged and place the machine out of use. Also the bricks or blocks are delivered close to the ground within handy reach of the workmen, and this is accomplished by mechanism which can be produced cheap enough to make it practical of employment by the ordinary contractor.

In use, the machine is placed on the previously laid pavement and moved along as the work progresses. The sides of the machine are brought close enough to the pile of bricks or blocks along the street to enable them to be placed on the conveyer of the machine, by which they are carried into position to be lifted off by the workmen and placed in position. The various controlling mechanisms allow the machine to be moved forward or backward, or around corners, and permit the conveyer to be moved clockwise or counter-clockwise, as desired.

I claim:

1. A machine for handling paving material, comprising a frame consisting of a side portion and a top portion, a conveyer carried by the side portion and lying intermediate the top and bottom thereof and traveling in a horizontal plane, oppositely-disposed tractor members secured to the frame and extending into the plane in which the conveyer is traveling, whereby said conveyer is brought close to the ground line, a motor on the top section, a driving connec-

- tion from the motor to the tractors, a shift-
able clutch member for enabling said trac-
tors to be driven in unison, and one inde-
pendent of the other, whereby a steering op-
eration can be effected, lever members on
5 said top section for actuating said clutch
mechanism, and a connection from said mo-
tor for driving said conveyer, substantially
as described.
- 10 2. A machine for handling paving mate-
rial, comprising a frame consisting of a
vertical side portion and a horizontal top
portion, an endless conveyer upon said side
portion and located intermediate the top
15 and bottom edges thereof, said conveyer
comprising a link belt, overlapping plates
pivoted to the upper side of said belt at one
inner corner of each plate, each of said
plates forming a receptacle to receive a pav-
20 ing block, said conveyer traveling in a hori-
zontal plane, tractor members carried by
said frame and extending into the plane in
which the conveyer is moving, whereby the
conveyer is brought close to the ground line,
25 and a motor for actuating the tractors and
conveyer carried by the top portion, sub-
stantially as described.
3. A machine for handling paving mate-
rial, comprising a hollow frame consisting
30 of a vertical side portion and a horizontal
top portion, tractor members carried by
said frame and extending upward and into
the hollow portion thereof to a point adjac-
ent the top portion, whereby said frame is
35 brought close to the ground line, a conveyer
carried by the side portion of said frame
and lying intermediate thereof and travel-
ing in a horizontal plane, and a motor car-
ried by the top portion for actuating the
40 conveyer and tractor members, substantially
as described.
4. A machine for handling paving mate-
rial, comprising a frame consisting of a vertical
side portion and a horizontal top portion,
said side portion being composed of 45
upper and lower angle bars to which a vertical
section is secured, the upper angle bar
having its horizontal portion turned inward
and forming a rail to which the upper por-
tion is secured, the lower angle bar having 50
its horizontal portion turned outward, a
conveyer upon said frame, said horizontal
portion of the lower angle bar forming a
trackway for said conveyer, said conveyer
traveling in a horizontal plane, tractor mem-
bers carried by the frame and extending into
55 the plane in which the conveyer is traveling,
whereby the conveyer is brought close to the
ground line, and a motor carried by the top
section for driving the conveyer and trac-
tor members, substantially as described. 60
5. In a machine for handling paving mate-
rial, the combination of a rectangular
frame comprising a vertical side portion
and a horizontal top portion, an endless con-
veyer carried by the side portion and lying 65
intermediate the top and bottom edges there-
of and traveling in a horizontal plane, driv-
ing members for said conveyer, said mem-
bers being mounted at each corner of the 70
side portion and extending partially within
and partially without said side portion
with the outwardly extending portions in
operative relation to the conveyer, tractor
members carried by the frame and ex- 75
tending into the plane in which the
conveyer is traveling, whereby the conveyer
is brought close to the ground line, and a
motor on the top section for actuating the
conveyer and tractor members, substantially 80
as described.
